UNITED STATES PATENT OFFICE.

GEORGE W. KIRKPATRICK, OF ROCHESTER, NEW YORK.

SPRINKLING DEVICE FOR FIRE PROTECTION.

1,147,513.

Specification of Letters Patent. Patented July 20, 1915.

Application filed August 12, 1911. Serial No. 643,714.

To all whom it may concern:

Be it known that I, GEORGE W. KIRKPATRICK, a citizen of the United States, and a resident of Rochester, in the county of Monroe and State of New York, have invented a new and improved Sprinkling Device for Fire Protection, of which the following is a specification.

This invention relates to sprinkling devices, the object being to provide a sprinkling device, preferably comprising a rotating sprinkling head with mechanism for controlling the direction of the stream or streams of liquid issuing therefrom in such a way as to overcome the tendency to a deflection thereof by a current of air.

In carrying out my invention I may make use of a revolving sprinkler head which is attached to a rotatable supply member, the parts being so conformed that the main direction of the spray or stream from the revolving sprinkler head is deflected from a perpendicular while the axis of the revolving sprinkler head is directed at any desired point of the compass. The supply member to which the revolving sprinkler head is attached is supported to rotate upon a vertical axis and by means of mechanism permitting the free rotation of the parts on such vertical axis, while the stream issuing therefrom is deflected from such vertical axis and is caused to impinge against and cause the rotation of the revolving sprinkler head. To the supply member I attach a wind vane adapted in its operation to direct the streams issuing from the sprinkler head against the wind or current of air.

In the accompanying drawings I have shown that embodiment of my invention adapted to use in protecting the roof of a building against fire without limiting myself, however, to such or any particular embodiment thereof.

Such drawings are as follows.—Figure 1 is a side elevation showing the rotatable supply member and the upper and lower ends of the extension to the supply pipe leading thereto shown partly in section. Fig. 2 is a transverse horizontal sectional view of the rotating supply member taken along the line $x-y$ of Fig. 1, while Fig. 3 is a plan view of a detail to be explained. Fig. 4 shows diagrammatically a sprinkling device in accordance with my invention supported at the apex or ridge of the roof of a building which is partially shown.

Similar parts are designated by similar reference characters throughout the several figures of the drawings.

Referring to the drawings.—H represents a part of the roof of the building to be protected extending upwardly through which is seen the supply pipe P in vertical central section making threaded engagement at its upper end with a fixed extension member D between the shouldered lower end d^1 of which and the upper end of the pipe P there is clamped the perforated metallic washer member w, the central orifice in which is adapted to rotatably receive the lower end of the rod R for the purpose to be explained.

Upon the roof H there may preferably be secured a tubular jacket member U extending upwardly within a hood member T carried by the enlarged lower end d^1 of the extension D to prevent the water from entering the building inside of the member U, at the bottom of which is seen a flange u for securing the same to the roof.

The rotating supply member E comprises a hollow casting and has extending across its lower and larger end a perforated member e into which there may be secured the upper end of the rod R freely rotatable as above mentioned in the member w and operating to brace the parts against the action of the wind and the reaction of the issuing stream. Onto the upper and smaller end of the member E there may be secured a sprinkler head, shown in this instance at S, as of a well known construction, having the revolving vane s thereon operating in the usual way to divide the issuing stream into a spray and throwing the same in all directions outwardly and away from the axis of its rotation.

The member E is provided on its convex side with a projecting flange v to which is secured the wind vane V by means of rivets or screws r. On the lower end of the member E there is threaded the collar C while the lower end of the member E and the collar C are conformed on their inner edges to comprise a suitable ball race cooperating with a race formed in the outer periphery of the enlarged head d on the extension pipe D to receive the balls b to form a ball bearing for the member E and the parts attached thereto to reduce the friction of the parts to a minimum. The member C may also be flanged as seen at s.

The operation of the device is as follows;—The apparatus being installed in the manner indicated in the drawings and the pipe P being connected, through the medium 5 of any suitable valve, with a suitable source of supply of water under pressure, the water as it is forced through the pipe P and extension D enters the member E and passes therethrough and outwardly therefrom at 10 the opening indicated in dotted lines in the upper left hand end of this member in Fig. 1 and impinges against the rotating vane s causing the same to rotate and is also deflected thereby into a fine spray while the 15 vane V operates to swing the member E upon its vertical axis in such a way as to deflect the stream issuing from the member E against the wind to cause the spray from the nozzle to be more evenly distributed over 20 the surface intended to be protected thereby.

What I claim is:

1. In a device for the purpose described, a supply pipe connected with a suitable source of liquid under pressure, a member forming 25 an extension to said supply pipe, an element rotatably connected with said extension member and having a passage therethrough terminating in an outlet adapted to discharge the liquid at an angle with the axis 30 of rotation of such element, a wind vane on said element, a bracing rod extending longitudinally of and within said extension member, means carried by said rotatable element for securely holding one end of said rod,

and a suitable bearing located in said pipe 35 extension within which the other end of said rod is freely rotatable, said rod adapted to brace the parts against the wind and the reaction of the issuing stream, and said vane adapted to control the direction of discharge 40 of the issuing stream.

2. In a device for the purpose described, a supply pipe connected with a suitable source of liquid under pressure, a member forming an extension to said supply pipe, 45 an element rotatably connected with said extension member and having a passage therethrough terminating in an outlet adapted to discharge the liquid at an angle with the axis of rotation of such element, a rev- 50 olable sprinkler head secured to the outer end of said element, a wind vane on said element, a bracing rod extending longitudinally of and within said extension member, means carried by said rotatable element for 55 securely holding one end of said rod, and a suitable bearing located in said pipe extension within which the other end of said rod is freely rotatable, said rod adapted to brace the parts against the wind and the reaction 60 of the issuing stream, and said vane adapted to control the direction of discharge of the issuing stream.

GEO. W. KIRKPATRICK.
